PAPERBOARD CARTON

Charles P. Wellman, North Haven, Conn.

Application September 15, 1937, Serial No. 163,895.

21 Claims. (Cl. 229—6)

This invention relates to a paperboard carton, and more particularly a carton adapted for the packaging and merchandising of radio tubes and like fragile articles.

It is an object of this invention to provide a carton formed from paperboard material, which protects the radio tube and like fragile article contained therein from possible damage resulting from exterior shock and which is provided with means to permit ejection of the test end of the tube so that the test end can be plugged into a socket and the tube tested without requiring removal of the tube from the carton.

Another object of this invention is to provide a carton for radio tubes and the like which permits limited sliding movement of the tube within the carton whereby ejection of the test end of the tube may be effected, the carton being so constructed that the tube cannot be removed without mutilating, destroying or rupturing the carton in such a manner as to visibly indicate that the carton has been tampered with.

Another object of this invention comprises the provision of a radio tube carton which can be economically formed and assembled from paperboard material with a minimum of hand operation and into which the radio tube or like article may be quickly and easily packed.

Other objects of this invention will become apparent as the disclosure proceeds.

Various other features and advantages of the invention will be apparent from the following particular description and from an inspection of the accompanying drawings.

Although the novel features which are believed to be characteristic of this invention will be particularly pointed out in the claims appended hereto the invention itself, as to its objects and advantages, and the manner in which it may be carried out, may be better understood by referring to the following description taken in connection with the accompanying drawings forming a part thereof, in which:

Fig. 1 is an extended view of a prepared blank from which the outer tubular member of the carton may be formed.

Fig. 2 is an extended view of a prepared blank from which the inner tube-supporting member may be formed;

Fig. 3 is a perspective view of the blank shown in Fig. 2 partially wrapped around a radio tube and an inner protective shell, this view illustrating one step in the process of packaging a tube in the carton;

Fig. 4 is a perspective view of the assembled outer tubular member ready to receive the inner tube-containing member;

Fig. 5 is a perspective view of the inner member assembled within the outer member with a strap portion associated with the outer mem-

ber in the process of being inserted into interlocking relationship beneath the strap associated with the inner member;

Fig. 6 is a perspective view of the fully assembled carton having a radio tube therein whose test end has been ejected into testing position, certain parts being broken away to more clearly illustrate the construction;

Fig. 7 is an extended view of a prepared blank from which a somewhat modified form of radio tube carton may be made;

Fig. 8 is an extended view of a prepared blank which, when assembled around the tube, provides an inner member adapted to be associated with the outer tubular member formed from the blank shown in Fig. 7;

Fig. 9 is a perspective view of the inner member formed from the blank shown in Fig. 8 wrapped around a radio tube and its associated protective shell in the process of being inserted into the tubular outer member formed from the blank shown in Fig. 7;

Fig. 10 is a perspective view of the radio tube carton formed from the blanks shown in Figs. 7 and 8 at a further stage of the assembly operation, this view particularly showing the strap portions associated with the inner member in the process of being inserted through spaced apertures in the outer member;

Fig. 11 is a perspective view of a completely assembled carton formed from the blanks shown in Figs. 7 and 8 wherein the inner sliding member is slidably sealed in the outer tubular member;

Fig. 12 is an extended view of a prepared blank from which one section of an inner-tube supporting member of somewhat modified construction may be made;

Fig. 13 is an extended view of a prepared blank from which is formed the companion section of the section formed from the blank shown in Fig. 12;

Fig. 14 is an extended view of a prepared blank from which a modified form of outer tubular member adapted to be associated with the inner tube-supporting sections illustrated in Figs. 12 and 13;

Fig. 15 is a perspective view of a radio tube housed within a protective shell, this view showing the inner sections formed from the blanks shown in Figs. 12 and 13 in the process of being wrapped around the tube and protective shell;

Fig. 16 is a perspective view of the prepared blank shown in Fig. 14 in the process of being formed into an outer tubular member which receives the tube and associated inner sections illustrated in Fig. 15;

Fig. 17 is a perspective view of the inner sections shown in Fig. 15 as they appear when fully

assembled around the tube and protective shell, the outer encasing member being shown in the process of being wrapped around the inner tube-supporting sections;

5 Fig. 18 is a vertical cross-sectional view of the carton illustrated in Fig. 17 as it appears when fully assembled, this view showing the carton in cross-section as it would appear if the section were taken through a finished carton at lines 18—18 of Fig. 17;

10 Fig. 18a is a vertical cross-sectional view through the carton illustrated in Fig. 17 as it appears when fully assembled, this view being taken along line 18a—18a of a fully assembled carton formed from the parts shown in Fig. 17;

15 Fig. 19 is another vertical cross-sectional view through the completed carton, this view showing the points where pressure may be applied to release the locking abutments which retain the test end of the tube in housed position within the outer tubular member;

20 Fig. 20 is a vertical cross-sectional view through the completed carton, illustrating more particularly the means for limiting the sliding movement of the inner member within the outer member, this view being taken through a completed carton as it would appear along the lines 20—20 of Fig. 17;

25 Fig. 21 is an extended view of a prepared blank from which an outer member of further modified form may be made;

30 Fig. 22 is an extended view of a prepared blank from which an inner tube-supporting member of further modified form may be made, which inner member is adapted to be associated with the outer encasing member formed from the blank shown in Fig. 21;

35 Fig. 23 is a perspective view of an inner member formed from the blank shown in Fig. 22 as it appears at one stage of the assembly operation;

40 Fig. 24 is a perspective view of the inner member shown in Fig. 23 as it appears at a further stage of the assembly operation;

45 Fig. 25 is a front elevational view of the inner member shown in Figs. 23 and 24 as it appears when fully assembled around a tube;

50 Fig. 26 is a perspective view of the outer member formed from the blank shown in Fig. 21 in the process of being wrapped around the inner tube-supporting member, certain parts being broken away to more clearly illustrate the construction;

55 Fig. 27 is a perspective view of the outer member shown in Fig. 26 at a more advanced stage of assembly around the inner tube-supporting member; and

60 Fig. 28 is a perspective view of the fully assembled and sealed carton illustrated in Fig. 27.

Similar reference characters refer to similar parts throughout the several views of the drawings and the specification.

65 Referring more particularly to Figs. 1 to 6 inclusive, a carton for radio tubes and the like is shown, said carton comprising an outer tubular member A formed from the blank illustrated in Fig. 1 containing an inner tube-supporting member B formed from the blank shown in Fig. 2. The outer tubular member A is formed from a substantially rectangular blank comprising side wall sections 1, 2, 3 and 4, defined by the vertically extending score lines 6. A securing flap 5 hinged to the side wall section 4 along the score lines 6 is coated with adhesive g so that the same may be secured to the side wall section 1 to rigidly 70 retain the blank in tubular form, as illustrated 75

in Fig. 4. A strap portion 7 defined by parallel extending cuts 8 extending transversely across side wall sections 3 and 4, provides means for limiting the sliding movement of the inner member within the outer tubular member, as will hereinafter be described.

The inner tube-supporting member B formed from the blank shown in Fig. 2 comprises an end wall portion 11 having a suitable aperture 20 therein through which the test end p of the tube may project. The end portion 11 also provides a support for the lower end of the tube T. Another end wall portion 12 seats over the top end of the tube and may be provided with a suitable aperture 21 therein to fixedly center the tube within the inner member. A side wall portion 13 hinged to the end wall portions 11 and 12 along the score lines 14 extends along one side of the tube. Another side wall portion formed by the flaps 15 and 16 hinged to the respective end wall portions 11 and 12 along the score lines 14 are positioned to extend along the opposite side of the tube. The side wall-forming flaps 15 and 16 may be suitably connected together by the provision of hook portions 24 and 25 associated with the flaps 15 and 16 respectively, which hook portions are adapted to be connected in interlocked relationship when the blank B has been wrapped around the tube T, as illustrated in Fig. 3. Leg portions 17 hinged to the end wall portion 11 along the score lines 18 provide a suitable support to hold the test end p of the tube out of contact with the supporting surface upon which the carton is positioned. Leg portions 19 hinged to the end wall portion 12 along the score lines 18 also provide a support which prevents the top end of the tube from contacting the supporting surface if the carton is placed in an inverted position. A strap portion 22 defined by the longitudinal cuts 23 extending for a predetermined distance through the side wall portion 13, provides means which, when assembled in interlocked relationship with the transversely extending strap portion 7 associated with the outer tubular member, operates to permit a limited sliding movement only of the inner member B supporting the tube T within the outer tubular member A.

In packaging a radio tube in the carton above disclosed, the tube may, if desired, be first positioned within a protective shell C. The test end p of the tube is inserted through the aperture 20 in the end wall portion 11; the end wall portion 12 is then swung over the top end of the tube and into engagement therewith so that the aperture 21 will operate to center the tube in proper position within the inner member. The side wall-forming flaps 15 and 16 are then firmly connected together by any suitable means. Such connecting means may comprise hook portions 24 and 25 associated with the side wall flaps 15 and 16 respectively, which hook portions may be connected together in interlocked position so as to securely retain the inner tube-supporting member in fixed wrapped position around the tube. Leg portions 17 and 19 are then turned outwardly, as illustrated in Fig. 3, and the inner member with the tube positioned therein is then telescoped into the outer tubular member previously assembled together, as shown in Fig. 4.

When the inner tube-supporting member has been fully inserted into the outer tubular member, the free end portion 10 of the strap 7 associated with the outer tubular member, is threaded through the spaced cuts 23 formed in the side wall portion 13 of the inner tube-support-

ing member so that the strap portion 7 associated with the outer tubular member will underlie the strap portion 22 associated with the inner tube-supporting member. This assembly operation is fully illustrated in Figs. 5 and 6. The strap portion is drawn through the cuts or apertures 23 until the end portion thereof is positioned adjacent a tab portion 9 extending from the free edge of the side wall section 4, as illustrated in Fig. 6. A suitable sealing element 26, such as a rivet, eyelet, staple, stitch, or other securing device, secures the tab portions 9 and 10 together in fixed, sealed relationship. The tab portion 10 may be coated with ink or other adhesive-resisting material so that when the adhesive *g* is applied to the securing flap 5 as shown in Fig. 1, by a strip gluing machine, the glue will not adhere to the face of the tab portion 10. Thus, the tab portions 9 and 10 are secured together entirely by the pilfer-proof eyelet 26, as illustrated in Fig. 6. The securing device 26 should be of such form that the same cannot be removed or detached without substantially and visibly mutilating or destroying the tabs 9 and 10 to which it is secured. An eyelet or rivet which is headed over to penetrate and grip the tab portions 9 and 10, has been found satisfactory for this purpose.

It will be noted that the length of the cuts 23 bears a predetermined relation to the transverse width of the strap portion 7 which extends therethrough, so that the inner tube-supporting member B is permitted to slide within the outer tubular member a limited predetermined distance only, as illustrated in Fig. 6. Thus, when the upper edge of the strap 7 abuts the ends 27 of the cuts 23, the test end *p* of the tube is fully ejected and readily insertable into a suitable test socket. When so positioned, the leg portions 17 may be swung outwardly so as not to interfere with the ready insertion of the test end *p* into the test socket. It will be noted by referring to Fig. 6, that the tube cannot be further ejected from the outer tubular member and the tube is fully protected at all times against damage, injury or substitution. After testing the tube, the test end may be retracted into protected position within the outer tubular member A, in which position the leg portions 17 are drawn into the outer tubular member, providing rigid supports for the tube. The leg portions 17 are of such width that when resting upon a supporting surface the test end *p* of the tube will be held suspended out of contact with a normally flat supporting surface.

Removal of the tube T and inner member through the top end of the carton is prevented by reason of the fact that when the tube is in the desired housed position within the outer tubular member, the lower edge 29 of the strap 7 will abut the lower ends 28 of the cuts 23, making further movement of the tube toward the upper end of the carton impossible. It will be noted that the side wall section 4 of the outer tubular member overlies the ends 27 and 28 of the cuts 23 and prevents tearing of the side wall portion 13 beyond the termini 27 and 28 of the cuts. Should the carton be positioned in inverted position the leg portions 19 will then contact the supporting surface to suspend the top end of the tube out of contact with the supporting surface.

The carton as illustrated in Figs. 1 and 6 is formed from substantially rectangular paper-board blanks, which can be prepared and assem-

bled entirely by automatic machinery at low cost and substantially without waste of material. The tube can be quickly encased within the inner tube-supporting member and the whole quickly telescoped into the outer tubular member. The inner and outer tubular members can be quickly locked together to permit limited sliding movement only of the inner member by drawing the strap 7 through the cuts 23 and beneath the strap portion 22. Automatic means may be provided for quickly applying the sealing eyelets 26 to the tabs 9 and 10. The strap portion 22 which is framed between the cuts 8 provides an attractive surface for applying various data to the carton, such as the date of manufacture of the tube, the date of sale of the tube to the customer, or other desired information. Such information can be conveniently imprinted upon the strap portion 22 prior to assembly or during assembly of the inner tube-supporting member.

A modified radio tube carton is illustrated in Figs. 7 to 11 inclusive, which carton comprises an outer tubular member A' formed from the blank shown in Fig. 7, and an inner tube-supporting member B' formed from the blank shown in Fig. 8. The outer tube-forming blank shown in Fig. 7 comprises side wall sections 31, 32, 33 and 34 hinged together along the score lines 36. A flap 35 hinged to the side wall section 34 along the score lines 36 is provided to secure the blank in tubular form, suitable adhesive *g* being applied thereto which adheres to the inside face of the side wall section 31. A small slit-like aperture 37 is provided at one end of the side wall section 31 and an enlarged rectangular opening 38 is provided adjacent the other end of the side wall section 31, which aligns with a similar opening 39 in the securing flap 35. It is thus seen that the slot 37 and the aligned openings 38 and 39 give limited access to the interior.

The inner tube-supporting member formed from the blank B' comprises an end wall portion 11 having the usual opening 20 therein through which the test end *p* of the tube projects and a top wall portion 12 extending over the top wall of the tube, having an opening 21 therein which serves to center the tube. The end wall portions 11 and 12 are connected together by a side wall portion 13 hinged to the end wall portions along the score lines 14. Outwardly turned legs 17 hinged to the end wall portion 11 along the score lines 18, support the test end of the tube out of contact with the supporting surface and, similarly, leg portions 19 hinged to the end wall portion 12 by the score lines 18 support the top end of the tube out of contact with the supporting surface should the carton be placed in inverted position. A strap portion 45 hinged to the end wall portion 11 is arranged so that it may be threaded through the slot 31 formed in the outer tubular member. The strap portion 46 hinged to the end wall portion 12 along the score lines 47 is likewise adapted to be inserted through the aligned openings 38 and 39 in the outer tubular member, as more particularly illustrated in Figs. 10 and 11. A tab portion 48 extending from the strap portion 45 and hinged thereto along the score lines 50 and tab portion 49 extending from the strap portion 46 and hinged thereto along the score lines 50, may be inseparably secured together by means of an eyelet 51 which cannot be removed or detached without rupturing the

paperboard material or otherwise leaving visible evidence of tampering.

In packaging the tube and assembling the carton, the tube T may be first placed within an inner protective shell C , the test end p of the tube is then inserted through the opening 20 in the end wall portion 11 and is supported thereon. The end wall portion 12 is positioned to overlie the top end of the tube, aperture 21 therein serving to center the tube. The leg portions 17 and 19 are bent outwardly and the inner member wrapped around the tube and inner protective shell. The assembly is then telescoped into the outer tubular member, as illustrated in Fig. 9. As the inner member is telescoped into the outer member, the tab portion 48 associated with the strap portion 45 is threaded through the slot 37. When the tube is substantially completely inserted within the outer member the tab portion 49 associated with strap 46 is threaded through the aligned openings 38 and 39 of the outer tubular member, as illustrated more particularly in Figs. 10 and 11. The rivet, staple, or eyelet 51 is then applied to secure the tab portions 48 and 49 inseparably together.

It will be noted that the tube assembled in the carton above described has a limited telescoping movement only within the outer tubular member. When the test end p of the tube has been sufficiently ejected from the lower end of the outer tubular member to permit convenient testing, the hinged edge 47 of the tab portion 46 will abut the lower edge 40 of the opening 38, preventing further ejection of the tube from this end of the carton. The tube cannot be drawn from the other end of the carton by reason of the fact that the end wall portion 11 of the inner member cannot travel inwardly of the outer member farther than the slot 37, being prevented from further movement in this direction by the strap portion 45 connected to the end wall portion 11 which extends through the slot opening 37. Such movement is further prevented by the tab portion 49 which moves into abutment against the upper edge 41 of the opening 38. The material 42 of the side wall 31 intermediate the slot 37 and the opening 38 is of substantial width and underlies the strap portions 45 and 46 and cannot be torn or otherwise mutilated to remove the tube without leaving visible evidence of tampering. The strap portions 45 and 46 are made of good quality paperboard material and possess substantial strength and cannot be released from interlocked relationship with the intermediate portion 42 of the outer tubular member without leaving immediate evidence of tampering. Cartons as shown in Figs. 7 to 11 inclusive can be economically manufactured, assembled and formed into a pilfer-proof package.

It will be noted that the cartons illustrated in Figs. 6 and 11 provide pilfer-proof eyelets 26 and 51 respectively, which are entirely exposed and visible, so that any tampering with the package to destroy the tabs to which these eyelets are secured would be immediately and strikingly obvious to the consumer or purchaser. It will be further noted, by referring to the carton shown in Fig. 6, that the tab portions 9 and 10 secured together by the eyelet 26 can be conveniently folded out of the way into the recess formed in the side wall section 4 of the outer member, this depression being formed at the place where the strap 7 emerges from beneath the strap 22, as illustrated in Fig. 6. Likewise, the tab portions 48 and 49 secured together by the pilfer-proof

eyelet 51, as shown in Fig. 11, can also be folded upwardly so as to lie against the strap portion 46 and in the depression formed in the side wall section 31 of the outer member. The tab portions 9 and 10, as illustrated in Fig. 6, and the tab portions 48 and 49, illustrated in Fig. 11, thus can be made to lie flat in the natural recesses provided in the outer carton so that they will not interfere with the shipment and storage of these cartons when placed in a packing case or when arranged on the merchant's shelf.

A further modified form of pilfer-proof carton for radio tubes and the like is illustrated in Figs. 12 to 20 inclusive, this carton being made from outer tubular member A^2 formed from the blank shown in Fig. 14 and an inner sliding member comprising sections B^2 and B^3 formed from the blanks shown in Figs. 12 and 13 respectively. The outer tube-forming blank, as shown in Fig. 14, comprises side wall sections 61, 62, 63 and 64 hinged together along score lines 66. A securing flap 65 hinged to the side wall section 64 along score lines 66 has adhesive g applied thereto which secures the flap to the free edge of the side wall section 61 and maintains the outer member in tubular form. Abutment flaps 67 extend from the respective side wall sections at one end of the carton, which abutment flaps may be folded downwardly against the inside face of the respective side wall sections 61, 62, 63 and 64 and, if desired, secured thereto by adhesive g , as illustrated in Fig. 16. The lower end of the outer tube-forming blank is provided with a pair of upwardly positioned abutment flaps 69 hinged to side wall sections 61, and 63, respectively, along the score lines 68 and secured to the inside face of said side wall sections by adhesive g , as illustrated in Fig. 16. Abutment flaps 70, which are somewhat longer than the abutment flaps 69, are hinged to the side wall sections 62 and 64 along the score lines 68 and are also secured to their associated side wall sections by adhesive g . The purpose served by the abutment flaps 67, 69 and 70 will be hereinafter brought out.

The inner tube-containing section B^2 formed from the blank illustrated in Fig. 12 comprises an end wall portion 81 having an aperture 20 through which the test end p of the tube T extends. An end wall portion 82 extends over the top end of the tube T ; the tube being suitably centered by an aperture 21 in the end wall portion 82. A side wall portion 83 hinged to the end wall portions 81 and 82 along the score lines 84 extends along one side of the tube. A side wall portion 85 hinged to the end wall portion 82 along the score lines 84 extends along the opposite side of the tube and is secured at its free end to the end wall portion 81 by means of a securing flap 80 hinged to the end wall portion 81, this attachment being made in any suitable manner, as by applying adhesive g to the flap 80.

A companion inner tube-supporting section B^3 is formed from the blank shown in Fig. 13, which blank is very similar to the blank shown in Fig. 12, heretofore described.

In loading the tube in the carton, the tube T may be inserted within an inner protective shell C' , of any suitable form, and the test end p of the tube is inserted through the opening 20 in the end wall portion 92 of section B^3 . The side wall portion 93 is then raised upwardly so as to extend along one side of the tube T and its associated protective shell C' , as illustrated in Fig. 15. The end wall portion 91 is then brought over the top end of the tube and the tube is suitably centered

therein by means of the opening 21. Side wall portion 95 hinged to end wall portion 92 along the score lines 94 may then be raised so as to overlie an opposite side wall face of the tube, the side wall portion 95 being secured as by adhesive *g* to the securing flap 80 hinged to the end wall portion 91 along the score lines 94. Section B³ thus forms a continuous band enclosure for the tube and its associated protective shell C'.

The inner tube-supporting section B² may then be applied by inserting the test end *p* of the tube through the opening 20 in the end wall portion 81, the end wall portion 81 overlying the end wall portion 92 of section B³. Side wall portion 83 is then raised to overlie an uncovered side of the tube T or protective shell C' and the end wall portion 82 brought into position to overlie the end wall portion 91 of section B³. Side wall portion 85 is secured to the end wall portion 81 by means of adhesive *g* applied to the securing flap 80. As thus assembled, the tube T and associated protective shell C' are entirely contained or enclosed within the bandlike tube-supporting sections B² and B³ in bandlike form.

When the inner tube-supporting sections B² and B³ have been fully assembled around the tube, as illustrated in Fig. 17, the outer tube-forming blank, assembled in the form shown in Figs. 16 and 17, is then wrapped around the inner assembled tube-supporting sections. In this connection it will be observed that abutment flaps 86 have been cut out of the side wall portions 83 and 85 along the cut lines 87, the abutment flaps 86 being turned upwardly along score lines 88. Similar abutment flaps 99 have been cut out from the side wall portions 93 and 95 along cut lines 91, and the abutment flaps 99 are also turned upwardly by bending same along score lines 98, as illustrated in Fig. 17. It will be noted that, as thus assembled, the abutment flaps 86 and 99 have a normal tendency to swing laterally but are naturally prevented by the enclosing side wall sections 61, 62, 63 and 64 of the outer tubular member. When the tube is conveniently housed within the outer tubular member, it will be carefully noted, by referring more particularly to Figs. 18, 19 and 20, that the free edge of the abutment flaps 86 and 99 will normally abut the abutment edges 71 of the flap portions 67 cemented to the inside face of the side wall sections of the outer tubular member. The abutment flaps 86 and 99 exert a resilient pressure against the inside face of side wall sections 61, 62, 63 and 64 and when the tube is fully housed within the carton as illustrated in Figs. 18, 19 and 20, the abutment edges 71 of the flaps 67 will substantially abut the free edges of the abutment flaps 86 and 99 and thus prevent removal of the tube from the upper end of the carton.

Adjacent the lower end of the carton, abutment flaps 89 are cut out from the side wall portions 83 and 85 along cut lines 87 and are folded downwardly along the score lines 88. The free edges of the abutment flaps 89 normally seat against the abutment edges 72 of the flaps 69 associated with the side wall sections 61 and 63 of the outer tubular member, as illustrated in Fig. 18. Ejection of the test end of the tube from its housed position within the outer tubular member is thus normally prevented and the test end of the tube is thus reasonably locked in housed position within the outer tubular member. Means for releasing the

abutment flaps 89 and flaps 69 will now be described.

The abutment flaps 89 normally resiliently press against the adjacent side wall sections 61 and 63 respectively, and are thus normally in abutment with the abutment edges 72 of the flaps 69. By exerting inwardly directed pressure on the abutment flaps 89 by the thumb and forefinger *h*, or other suitable means, as illustrated in Fig. 19, the abutment flaps 89 may be pushed out of abutting engagement with the flaps 69 and the test end of the tube thus fully ejected. The application of this pressure to side wall sections 61 and 63 may be facilitated by either cutting an opening in the side wall sections 61 and 63 or, preferably, by making a cut 14 in the side wall sections 61 and 63 lying adjacent the abutment flaps 89 so as to provide a flap portion 15 which will readily swing inwardly when inwardly directed external pressure is applied thereto. Thus, by merely applying pressure directed against the abutment flaps 89, the tube may be unlocked from its housed position within the outer tubular member and readily ejected for test purposes. When the test has been completed the tube may be slid back into the carton and due to the resilient nature of the abutment flaps 89 they will readily snap into abutting engagement with the abutment edges 72 of the flaps 69.

To limit the ejected position of the test end of the tube, abutment flaps 96 are cut out from the side wall portions 93 and 95 of the inner section B³ along cut lines 97 permitting the abutment flaps 96 to be turned downwardly along the score lines 98. As thus arranged, the free edges of the abutment flaps 96 are arranged to be moved into abutting relationship with the abutment edges 73 of the flaps 70 associated with the outer tubular member. When the tube is completely housed within the outer tubular member, as shown in Fig. 20, the free edges of the abutment flaps 96 and the abutment edges 73 of the flaps 70 are spaced a predetermined distance apart, which distance is designated *a* in Fig. 20. When the test end *p* of the tube, however, has been brought to the proper ejected position for test purposes, the free edges of the abutment flaps 96 will then abut the abutment edges 73 of the flaps 70 and thus positively prevent further ejecting movement of the tube.

It will be noted that the abutment flaps 86 and 99 cooperating with the flaps 67 on the outer tubular member and the abutment flaps 96 cooperating with the flaps 70 on the outer tubular member, are so arranged and constructed that their abutting relationship cannot be released or disengaged to permit removal of the tube from the carton without requiring visible mutilation and destruction of the walls of the carton. The tube, however, is free to slide within the outer tubular member a distance sufficient to permit convenient testing of the tube, the length of the sliding movement permitted being governed by the distance *a*, as shown in Fig. 20. As shown in Figs. 18, 19 and 20, the carton is so constructed that neither end of the tube can touch the supporting surface upon which the carton rests, whether the carton is in upright or in inverted position. The test end of the tube cannot be ejected from its housed position until the abutment flaps 89 have been released from their locking abutment with the abutment edges 72 of the flaps 69, in the manner heretofore described. The carton here shown can be economi-

cally manufactured from substantially rectangular blanks of paperboard material and when assembled presents an unusually neat and attractive carton.

- 5 To further protect the customer against possible pilfering or tampering with the tube contained in the carton, eyelets 26 may be provided to further secure the securing flap 65 to the side wall section 61. Referring more particularly to
 10 Figs. 17 and 18a, the securing flap 65 may be inserted between the abutment flaps 67 and 69 and the side wall section 61 before the abutment flaps 67 and 69 are secured as by adhesive *g* to side wall section 61. Pilfer-proof eyelets 26
 15 can then be inserted to extend through the abutment flaps 67, securing flap 65 and the side wall section 61, and by another pilfer-proof eyelet which extends through the abutment flaps 69, the securing flap 65 and the side wall section 61. As thus arranged, it would be impossible to
 20 unwrap the outer member A² without tearing or lacerating the outer member.

A further modified form of pilfer-proof carton adapted for use in the packaging of radio tubes and like fragile articles, is illustrated in
 25 Figs. 21 to 28 inclusive of the drawings, this carton being made from an outer member A³ formed from the blank shown in Fig. 21, which houses and contains an inner tube-supporting member
 30 B⁴ formed from the blank shown in Fig. 22.

The inner tube-supporting member B⁴ is formed from a single strip of paperboard material comprising an end wall portion 141 having an opening 156 therein through which the test end of the tube extends, in the manner illustrated in Figs. 25 and 26. A secondary end wall portion 145 overlies the end wall portion 141 and is spaced therefrom by a spacer portion 146 hinged to the end wall portion 145 along the score line 147 and to the end wall portion 141 along the score line 148. A side wall portion 143 is arranged to extend along one side of the tube T and is hinged to the end wall portion 141 along the score line 144. A flap portion 151 hinged to the secondary end wall portion 145 along the score line 168 is positioned to lie against the inside face of the side wall portion 143 and is suitably secured thereto as by means of a hook portion 152 which is inserted through
 35 a horizontal cut 169 in the side wall portion 143, in the manner illustrated in Figs. 23 to 25 inclusive. The secondary end wall portion 145 is provided with an opening 155 through which the lower body of the tube projects, as illustrated
 40 in Figs. 25 and 26, thus serving to steady the tube in the carton.

The tube-supporting member B⁴ is also provided with an end wall portion 142 hinged to the side wall portion 143 along the score line 144 and is arranged to overlie the top end of the tube, an aperture 157 being provided therein to properly center the tube. A secondary end wall portion 150 underlies the end wall portion 142 and is spaced therefrom by means of a
 45 spacing portion 149 hinged to the end wall portion 142 along the score line 148 and hinged to the secondary end wall portion 150 along the score line 147, all in the manner illustrated in Figs. 24 and 25. A flap extension 153 hinged to
 50 the secondary end wall portion 150 along the score line 168 is positioned to lie against the inside face of the side wall portion 143 and may be secured thereto by providing a hook portion 154 on the flap extension 153 which is inserted
 55 through a cut 170 in the side wall portion 143,

as illustrated in Figs. 24 and 25. As thus assembled, the inner tube-supporting member will appear as illustrated in Fig. 24. The inner member may also be provided with outwardly turned leg portions 159 hinged to the end wall portion 141 along the score lines 167 and outwardly turned leg portions 160 hinged to the end wall portion 142 along the score line 167. The leg portions 159 and 160 serve a useful purpose, as will presently appear.

The outer member A³ formed from the blank shown in Fig. 21, is provided with side wall sections 101, 102, 103 and 104 hinged together along the score lines 106, which side wall sections surround the enclosed tube. An end wall section 107 hinged to the side wall section 103 along the score line 109, is provided with an opening 119 through which the test end *p* of the tube may be projected. An end wall section 108 hinged to the side wall section 103 along the score line 109 closes the upper end of the carton except for an aperture 120 therein through which a suitable instrument may be inserted to effect ejection of the test end *p* of the tube. The end wall sections 107 and 108 may be joined along opposite side edges thereof by means of inwardly turned flaps 110 and 111 hinged to the end wall sections 107 along the score lines 106, and inwardly turned flaps 112 and 113 hinged to the end wall section 108 along the score lines 106.

When the tube T has been positioned within the assembled inner member, as shown in Figs. 25 and 26, the end wall section 107 is swung under, the test end *p* of the tube, and the end wall section 108 is swung into position to overlie the upper end of the tube. Flaps 110 and 112 are then swung into position to overlie one side of the tube, these flaps being suitably connected together as by hook portions 117 and 118 respectively associated therewith. The opposite flaps 111 and 113, as shown in Fig. 26, are swung into position to overlie the opposite side of the tube and are also suitably connected together as by hook portions 115 and 116 respectively associated therewith.

When the end wall sections 107 and 108 have been positioned over the ends of the tube and the sections connected together by connecting the flap 110 to 112 and flap 111 to 113, in the manner above described, the side wall section 102 is swung into position so as to overlie the flaps 110 and 112 and the side wall section 104 is swung into position so as to overlie the flaps 111 and 113, as illustrated in Figs. 26 and 27. A securing flap 105 is hinged to the side wall section 104 along the score line 106, and flap 105 is then swung into position so as to overlie the spacing portions 146 and 149 of the inner tube-supporting member. A flap 133 hinged to the end wall section 107 along the score line 135 is then swung upwardly so as to overlie the securing flap 105. Likewise a flap 134 hinged to the end wall section 108 along the score line 135 is swung downwardly to overlie securing flap 105. When this has been accomplished the side wall section 101 is positioned to overlie the securing flaps 105, as illustrated in Fig. 28.

Side wall section 101 is fixedly secured to the securing flap 105 so that these parts cannot be released without first requiring destruction of the carton. Such securing means may comprise a pair of spaced tab portions 121 and 123 cut from the side wall section 101 along cut lines 122. Corresponding tab portions 124 and 126 may be cut from the securing flap 105 along the

cut lines 125. When the side wall section 101 has been suitably positioned to overlie the securing flap 105, it will be noted that the tab portion 123 will overlie and abut the tab portion 126 so that an eyelet, rivet or other securing means 180 may be used to permanently secure these tab portions together. Likewise, tab portion 121 will then abut against tab portion 124 so that these tab portions may be secured together by a similar rivet, eyelet or other securing means 180. Access to the tube within the carton which would permit its withdrawal from the carton is thus effectively prevented. The tube cannot be withdrawn without first destroying the carton itself.

15 When the inner member has been assembled within the outer member and the tube fully housed therein, the leg portions 159 will normally rest upon the end wall section 107 of the outer containing member, as illustrated in Fig. 26. Similarly, the leg portions 160 hinged to the end wall portion 142 will abut the end wall section 108 of the outer member, as illustrated in Fig. 26. The leg portions 160 thus cushion the upper end of the tube and prevent this end of the tube from coming into contact with the end wall section 108 or otherwise becoming damaged through external shock delivered against the end wall section 108.

It will be appreciated that leg portions 159 normally would prevent ejection of the test end of the tube through the test aperture 119 in the end wall section 107. To permit ejection of the test end of the tube, means are provided whereby inward pressure may be externally applied against the leg portions 159 so as to force them to collapse and lie substantially flat against the inside face of the end wall section 107. Such inwardly directed external pressure may be conveniently applied by the fingers in the construction here shown, wherein a cut 131, which may be of generally arcuate form, is made in each of the side wall sections 102 and 104 at a point adjacent the leg portions 159. The cuts 131 define a resilient flap 130 which can be easily pressed inwardly with the fingers. In order that the external force applied to the flaps 130 may be readily transmitted to the leg portions 145 and effect inward swinging movement thereof, an arcuate cut-out opening 128 defined by cut edge 129 adjacent the cut 131 may be provided in the flaps 110 and 111 of the outer tubular member. The cut-out openings 128 are positioned in alignment with the flaps 130, thus making it relatively easy to transmit the externally applied inwardly compressive force against the leg portions 159 to swing the leg portions 159 into substantially horizontal or flat position and consequently permit convenient ejection of the test end *p* of the tube through the test opening 119. When the

50 tube is returned to its housed position within the outer member, the leg portions 159, possessing an inherent resiliency, will automatically swing outwardly to a raised or upright position and thus be brought into rigid abutment against the end wall section 107 which prevents a further ejection of the test end of the tube without again moving the leg portions 159 into horizontal position. The leg portions 159 also serve to cushion the lower end of the tube and protect the tube from damage resulting from external shock. A limited telescoping movement of the tube within the outer containing member can thus be effected, but the tube itself cannot be removed from the carton without visibly destroying the carton itself.

It will be noted that the carton shown in Fig. 28 is provided with cooperating tab projections 121 and 124 secured together by a pilfer-proof eyelet 180 and tab portions 123 and 126 secured together by a pilfer-proof eyelet 180. The recesses formed by the punching out of the tab portions 121 and 123 provide natural recesses in which the connected tab portions may reside so that these tab portions can be folded over into the recesses and thus disposed out of the way during shipment and storage of the carton.

It is now seen that I have provided several cartons adapted to contain radio tubes and like fragile articles which are so constructed as to permit limited telescoping movement of the tube 15 within the carton so that testing of the tube can be readily executed. The carton is so constructed, however, that removal of the tube from the carton cannot be accomplished without visibly destroying, lacerating, or demolishing the carton 20 within which the tube is contained. Means are further provided in the cartons herein disclosed for normally locking the tube and the test end thereof in housed position within the carton, which means can be readily released upon a pre-determined manipulation of the locking parts to 25 permit limited ejection of the test end of the tube. The cartons herein disclosed are furthermore so constructed as to prevent the tube from coming into contact with any surface upon which the 30 carton is supported, means being further provided to cushion the tube within the carton so that the tube cannot be damaged through the delivery of external shock to the carton itself.

The cartons herein disclosed may be conveniently made of paperboard material substantially without waste through the use of automatic cutting, scoring and gluing machines in common use. These cartons are so constructed as to permit quick loading thereof with a tube, means being 40 provided to effect quick and positive sealing of the carton which cannot be removed without requiring severe laceration or destruction of the carton itself.

While certain novel features of the invention 45 have been disclosed and are pointed out in the annexed claims, it will be understood that various omissions, substitutions and changes may be made by those skilled in the art without departing from the spirit of the invention.

What is claimed is:

1. A container for radio tubes and the like including, an outer tubular member, an inner tube-supporting member slidably positioned within said outer member, and means for limiting the 55 telescoping movement of said inner member within said outer member, said means including, a strap portion extending longitudinally of said inner sliding member, a strap portion extending transversely of said outer tubular member slidably interlocked to said first-named strap portion, and means for fixedly securing said first strap portion to said inner sliding member and said second strap portion to said outer tubular member whereby said strap portions cannot be 60 removed, detached or ruptured without leaving visible evidence of tampering.

2. A container for radio tubes and the like including, an outer tubular member, an inner tube-supporting member enclosing said tube and slidably positioned within said outer member, and means for limiting the telescoping movement of 70 said inner member, said means including, a strap portion fixedly secured to each of said inner and outer members respectively, said straps being ar- 75

ranged in interlocked relationship whereby said tube cannot be removed from the container without leaving visible evidence of tampering.

3. A container for radio tubes and the like including, an outer tubular member, an inner tube-supporting and enclosing member slidably positioned within said outer member, a strap portion fixedly secured to said inner member overlying a strap portion fixedly secured to said outer member and extending transversely thereof, the length of one of said strap portions and the relative width of the other of said strap portions being such as to permit limited sliding movement only of said inner member.

4. A container for radio tubes and the like including, an outer tubular member having enclosing side walls, an inner tube-supporting and enclosing member slidably positioned within said outer member, and means for limiting the telescoping movement of said inner member, said inner member having a strap portion fixedly secured thereto and extending through spaced openings cut in a side wall of said outer tubular member so that said strap portion overlies the intervening portion of said outer side wall.

5. A container for radio tubes and the like including, an outer tubular member, an inner tube-supporting and enclosing member slidably positioned within said outer member, and means for limiting the telescoping movement of said inner member, said means including an element fixedly secured to said inner member extending through spaced openings in said outer member and overlying the exterior face of an element defined between said spaced openings fixedly secured to said outer member, which elements cannot be removed, detached or ruptured without leaving visible evidence of tampering.

6. A container for radio tubes and the like including, an outer tubular member, an inner tube-supporting and enclosing member slidably positioned within said outer member, and means for limiting the telescoping movement of said inner member, said means including, an element integrally formed with said inner member extending through spaced openings in said outer member and overlying the exterior face of an element defined between said spaced openings and integrally formed with said outer member, which elements cannot be removed, detached or ruptured to effect removal of the tube from the container without leaving visible evidence of tampering.

7. A container for radio tubes and the like including, an outer tubular member having enclosing side walls, an inner tube-supporting member slidably positioned within said outer member, and means for limiting the telescoping movement of said inner member, said means including, a strap portion associated with said inner member extending through spaced apertures provided in a side wall of said outer member, said strap portion overlying the intervening part of said side wall defined by said apertures, said apertures being of such form as to permit limited movement of said strap portion and its associated inner member.

8. A container for radio tubes and the like including, an outer tubular member, an inner tube-supporting member slidably positioned within said outer member, said inner member including, spaced end wall portions and side wall portions connected to said end wall portions, and means for limiting the telescoping movement of said inner member, said means including, a strap por-

tion fixedly secured to said outer member looped under a side wall portion of said inner member.

9. A container for radio tubes and the like including, an outer member having enclosing side walls, an inner tube-supporting and containing member slidably positioned within said outer member, said inner member including spaced end wall portions and a side wall portion connecting said end wall portions, and means for limiting the telescoping movement of said inner member, said means including, a strap portion integrally formed in said inner member and defined by a pair of spaced, substantially parallel cuts made in a side wall portion thereof, said strap portion extending through spaced cuts in the adjacent side wall of said outer member, the relationship of said cuts being such as to permit limited sliding movement only of said inner member.

10. A container for radio tubes and the like including, an outer tubular member having enclosing side walls, an inner tube-supporting and enclosing member slidably positioned within said outer member, said inner member including spaced end wall portions and side wall portions connecting said end wall portions, and means for limiting the telescoping movement of said inner member within said outer member, said means including, a strap portion associated with said inner member defined by a pair of spaced substantially parallel cuts made in a side wall of said inner member, said strap portion extending through cuts made in a side wall of the outer member, the cuts in the side wall of the outer member extending substantially transversely of the cuts in the side wall portion of the inner member, the relationship of said cuts being such as to permit limited sliding movement only of said inner member within said outer member.

11. A container for radio tubes and the like including, an outer member having enclosing side walls fixedly secured together to form a tubular body, an inner tube-supporting and enclosing member slidably positioned within said outer member, said inner member including spaced end wall portions and side wall portions connecting said end wall portions, and means for limiting the telescoping movement of said inner member within said outer member, said means including, spaced, substantially parallel extending apertures formed in a side wall of said outer member and extending substantially transversely thereof to define an intermediate strap portion, said inner member having a side wall portion thereof extending through the apertures in said outer member and overlying the intermediate strap portion thereof, the apertures in said outer member being so arranged as to permit only limited sliding movement of said inner member within said outer member.

12. A container for radio tubes and the like including, an outer member having enclosing side walls fixedly secured together to form a tubular body, an inner tube-supporting and enclosing member slidably positioned within said outer member, said inner member including spaced end wall portions and side wall portions connecting said end wall portions, and means for limiting the telescoping movement of said inner member within said outer member, said means including, a longitudinally extending strap portion fixedly secured to said inner member defined by spaced, longitudinally extending cuts in a side wall portion of said inner member, and a strap portion formed in a side wall of said outer

member defined by spaced, transversely extending cuts in said side wall, said strap portion associated with said outer member being arranged to underly the strap portion associated with said inner member, said strap portions being of such width and length as to permit limited sliding movement only of said inner member within said outer member.

13. A container for radio tubes and the like including, an outer member having enclosing side walls fixedly secured together to form a tubular body, an inner tube-supporting and enclosing member slidably positioned within said outer member, said inner member including spaced end wall portions and side wall portions connecting said end wall portions, and means for limiting the telescoping movement of said inner member within said outer member, said means including, a longitudinally extending strap portion associated with said inner member, spaced transversely extending apertures cut in the side wall of said outer member defining an intermediate portion over which said strap portion associated with the inner member overlies, one of said apertures in said outer member having a predetermined width extending longitudinally of the side wall providing limited movement of said strap portion and its associated inner member.

14. A container for radio tubes and the like including, an outer member including enclosing side walls fixedly secured together, an end wall at each end of said outer member integrally formed with a side wall thereof, interlocking means connecting said end walls, and an inner tube-supporting member slidably positioned within said outer member, said inner member including partition portions extending over the ends of said tube, and means for connecting said end portions, one of said end walls of the outer member having an opening therein through which the test end of the tube may be ejected.

15. A container for radio tubes and the like including, an outer member including enclosing side walls fixedly secured together, an end wall at each end of said outer member integrally formed with a side wall thereof, interlocking means connecting said end walls, and an inner tube-supporting member slidably positioned within said outer member, said inner member including partition portions extending over the ends of said tube, and means for connecting said end portions, one of said end walls of the outer member having an opening therein through which the test end of the tube may be ejected, and releasable interlocking means associated with said inner and outer members whereby the test end of the tube is normally held in housed position within said outer member, and means in said outer member giving manipulative access to said interlocking means whereby said interlocking means may be released to effect ejection of the test end of the tube as desired.

16. A carton formed from a single blank of paper-board material including, enclosing side wall sections, an end wall section extending from each end of a side wall section, flaps extending from opposite side edges of each of said end wall sections, said flaps being enclosed within said side wall sections, means for connecting corresponding opposite flaps of the spaced end wall sections together, and means for connecting said side wall sections in tubular form.

17. A pilfer-proof container for a radio tube comprising, an outer containing member, an in-

ner tube-supporting member telescoping within and movable in relation to said outer containing member a distance sufficient to eject the test end of the tube for test, said inner member having a tube-supporting platform for supporting the test end of the tube, cooperating means associated with said inner and outer members for limiting the telescoping movement of said tube-supporting platform, means including a pair of tabs projecting beyond the outer surface of said outer member, and means for permanently sealing said tabs together whereby to prevent opening of said outer member or the removal of said inner member or the tube supported thereby without leaving visible evidence of tampering.

18. A pilfer-proof container for a radio tube comprising, an outer member having enclosing side walls, and an inner tube-supporting member movable within said outer member a distance sufficient to eject the test end of the tube for test, said inner member having a tube-supporting platform for supporting the test end of the tube, said platform having an opening through which the test portion of the tube projects, cooperating means associated with said inner and outer members for limiting the telescoping movement of said tube-supporting platform, means including a pair of tabs projecting beyond the outer surface of said outer member, and means for permanently sealing said tabs together whereby to prevent opening of said outer member or the removal of said inner member or the tube supported thereby without leaving visible evidence of tampering.

19. A carton formed from a single blank of paperboard material including, enclosing side wall sections connected together to provide a generally tubular construction, an end wall section at each end of the carton each hinged to one of said side wall sections, flaps hinged to opposite side edges of each of said end wall sections normally enclosed within said side wall sections when the carton is assembled, hook elements associated with each of said flaps for connecting corresponding flaps of the spaced end wall sections together, and an inwardly extending flap hinged to another side edge of each of said end wall sections.

20. A protective member for fragile articles formed from a single blank of paperboard material including, a pair of spaced primary end sections hingedly connected to a side wall section, each of said primary end sections having a secondary end section hingedly connected thereto by a spacing element, each of said secondary end sections having a hook portion adapted to be operatively connected to said side wall section.

21. A protective member for fragile articles formed from a single blank of paperboard material including, a pair of spaced primary end sections hingedly connected together through the medium of a side wall section, each of said primary end sections having a secondary end section hingedly connected thereto by a spacing element, each of said secondary end sections having hook means for connecting said secondary end sections to said side wall section, each of said primary and secondary end sections having an aperture therein through which the fragile article may project so as to retain the article in fixed position within the protective member.

CHARLES P. WELLMAN.
